HEEL-COVERING MACHINE

Lewis J. Bazzoni, Swampscott, Mass., assignor
to United Shoe Machinery Corporation, Pat-
erson, N. J., a corporation of New Jersey

Application December 27, 1934, Serial No. 759,388

19 Claims. (Cl. 12—42)

This invention relates to machines for use in the manufacture of shoes and is illustrated herein as embodied in a machine for covering heels.

In an application for United States Letters Patent Serial No. 56,739, filed December 30, 1935, in my name, there is disclosed a machine for applying a single piece of covering material to the rear and side faces of a heel and for inturning the top, the bottom, and the forwardly projecting margins of the cover against the marginal portions of the attaching, the top-lift receiving, and the breast faces of the heel, respectively. In order to complete the covering of Cuban heels, for example, which have been partially covered by the use of the above-identified machine, it is common practice for the operator, after trimming the forwardly projecting portions of the side cover to the desired widths, to apply the flap to the breast of the heel by hand, the margins of the forwardly projecting portions of the cover being applied to the median portion of the heel breast in overlapping relation.

It is an object of this invention to provide a machine which may be advantageously used to trim the forwardly projecting portions of side covers of heels to the desired widths and to lay such portions upon the breasts of the heels in overlapping relation. With the above objects in view and in accordance with a feature of this invention there is provided in a covering machine means for supporting a work piece, means for trimming the projecting margins of a cover secured to the work piece to widths suitable to insure that the margins shall overlap each other when applied to the work piece, and means for laying the trimmed margins in overlapping relation upon the work piece.

The invention is illustrated with reference to a machine constructed and arranged to trim the forwardly projecting portions of a cover, which have been secured to the side and rear faces of a heel, to desired widths, and to lay the trimmed projecting portions of the cover in overlapping relation upon the breast of the heel. The heel is positioned in the machine through the provision of suitable gages and is then clamped in position. In order to trim the forwardly projecting portions of the cover to the desired widths the machine is provided with a reciprocating cutting blade which is laterally curved in accordance with the heightwise curvature of the breast of the heel, the blade being supported by a carrier and having cutting edges which project widthwise of the heel and beyond the carrier. The carrier is normally in a centralized position adjacent to

the median portion of the breast of the heel and is yieldingly movable widthwise of the breast. In order to brace the forwardly projecting portions of the side cover against the cutting pressure of the blade and to lay the forwardly projecting portions upon the heel breast, the machine is provided with a unit mounted for swinging movement about an axis which passes substantially through the center of transverse curvature of the breast of the positioned heel. The unit comprises a pair of anvils which successively bend the respective forwardly projecting portions of the cover toward the heel breast and force the margins of the same against the respective cutting edges thereby to cause the blade to trim the margins to predetermined widths. The unit also comprises a resilient roll positioned between the anvils for laying the forwardly projecting portions of the cover in overlapping relation upon the breast of the heel.

In order to enable the roll to lay the trimmed margins in overlapping relation upon the median portion of the breast of the heel the blade carrier is alternately moved by the unit in opposite directions transversely of the heel breast from its centralized position. The unit is moved toward the heightwise median plane of the heel from one side of the heel to trim and to lay one of the forwardly projecting portions of the cover and is then swung toward the plane from the other side of the heel to trim and lay the other forwardly projecting portion of the cover. The amount of overlap of the forwardly projecting portions of the breast of the heel is controlled by the distance of the cutting edges of the blade from the heel breast. The illustrated machine is of simple construction and trims and lays the forwardly projecting portions of the side cover quicker and more uniformly than is possible by the present hand trimming and laying operation.

These and other features of the invention, including certain details of construction and combinations of parts, will be described as embodied in an illustrated machine and pointed out in the appended claims.

In the drawings,

Fig. 1 is a perspective view of the illustrated machine in the process of applying a forwardly projecting portion of a side cover of a heel to the breast of the heel;

Fig. 2 is a side elevational view of the machine, portions of which are shown in section;

Fig. 3 is a sectional view of the machine taken along line III—III of Fig. 2;

Fig. 4 is a sectional view similar to that illus-

trated in Fig. 3 but showing the relative positions of the parts of the machine at a later stage of the covering operation;

Fig. 5 is an enlarged perspective view partly in section, of mechanism for supporting a cover-trimming cutting blade of the machine;

Fig. 6 shows in perspective a heel which has been covered by the above mentioned machine disclosed in application for United States Letters Patent Serial No. 56,739; and

Fig. 7 shows the heel illustrated in Fig. 6 after the forwardly projecting margins of the cover of the heel have been trimmed and have been laid upon the breast of the heel.

The illustrated machine is described with reference to laying the forwardly projecting portions 20 of a cover 22 which has been attached to the rear and side faces of a heel 24 and is commonly known as a side cover, upon the breast 26 (Figs. 3 and 6) of the heel in overlapping relation. The side cover 22 may be laid upon the side and rear faces of the heel and inturned slightly upon the lateral margins of the top-lift receiving, the attaching and the breast faces of the heel 24, as illustrated in Fig. 6, by the use of the machine disclosed in the above-mentioned application for United States Letters Patent Serial No. 56,739. The cover is then snipped in the vicinity of the upper and lower breast corners of the heel to insure that the cover may be laid smoothly upon the heel.

The forwardly projecting portions 20 of the side cover are applied to the breast 26 of the heel 24 positioned and clamped in the machine, by a roll 28 which is preferably made of resilient material such as rubber and is rotatably supported by a bracket 30 which is screwed to sleeves 32 mounted upon a rod 34. Mechanism for positioning and clamping the heel in the machine will later be disclosed in detail. The sleeves 32 may be rotated by a hand wheel 36 or may be operated by a crank lever (not shown) driven by a power-operated clutch (not shown) or other suitable mechanism constructed and arranged to produce the desired swinging movement of the bracket 30. Extending lengthwise of the bracket 30 along opposite sides respectively of the roll 28 are a pair of anvils 37, 38 which may be made of suitable material and are constructed and arranged to bend the respective forwardly projecting portions 20 of the side cover toward the heel breast 26 as the bracket 30 is swung toward the heightwise median plane of the positioned heel. The anvils 37, 38 are also constructed and arranged to engage the cutting edges 40, 41, respectively, of a cutter or cutting blade 42 supported by a carrier 44. The roll 28 and the anvils 37, 38 swing as a unit.

The roll 28 is concave lengthwise in accordance with the heightwise curvature of the breast 26 of the heel and progressively lays the forwardly projecting portions 20 against the breast, the bracket 30 being temporarily stopped when opposing anvils 37, 38 (Fig. 3) have forced corresponding projecting portions 20 against cutting edges 40, 41, respectively.

The carrier 44 is pinned to the rod 34 and is normally urged to a position above the median portion of the heel breast 26, as illustrated in Fig. 3, and is swung under pressure of the anvils 38, 37 in clockwise and counterclockwise directions (Fig. 3), respectively, after corresponding projecting portions 20 of the cover have been trimmed. In order to cause the carrier 44 normally to assume the centralized position illus-

trated in Fig. 3 and to permit the same to be swung under pressure of the anvils 37, 38, a block 46 (Figs. 1 and 2) is pinned to the shaft 34 and engages the upper face of a slide 48 which moves along guides 50 screwed to the main frame and is normally forced upwardly by a spring 52. When the upper end of the slide 48 and the lower face of the block 46 are in surface engagement the carrier 44 is in a centralized position.

In order to trim surplus material from the forwardly projecting portions 20 of the cover when the margins of the same are forced against the cutting edges 40, 41 by the anvils 37, 38, respectively, the blade 42 is mounted for movement lengthwise of its cutting edges. The blade 42 is guided for movement lengthwise of its cutting edges 40, 41 by a plate 54 (Fig. 5) which is positioned between upper and lower carrier portions 56, 58, respectively, secured together by screws 60, the blade 42 being provided with an elongated slot 62 constructed and arranged to receive the plate 54. The blade 42 is normally moved to a rearward position by a spring 64 (Fig. 2) the respective ends of which engage the carrier 44 and a lug 66 (Fig. 2) screwed to the rear end of the blade 42. Rearward movement of the blade 42 under pressure of the spring 64 is limited by engagement of the blade with the end 67 of the plate 54. In order to reciprocate the blade 42 against the resistance of the spring 64 there is provided a slide 68 (Fig. 2) which is mounted for vertical movement in the frame of the machine and has a cam face 70 formed at its upper end. Upward movement of the slide 68 which is operated by a hand lever 72 causes the cam face 70 to force the blade forwardly. The lateral portions of the cam face 70 are slightly rounded to permit the lug 66 to ride up the cam face as the carrier 44 is moved from a lateral to a central or neutral position.

After the left forwardly projecting portion 20 (Fig. 3) of the side cover has been trimmed to the proper length the hand wheel 36 is rotated to swing the roll 28 across the median portion of the breast 26 of the heel 24, thereby to cause the same to lay the margin of the forwardly projecting portion of the cover upon the median portion of the heel breast. It will be noted that the carrier 44 is swung under pressure of the anvils 37, 38 in order to permit the roll 28 to move across the median portion of the breast 26 of the heel. The blade 40 is spaced from the breast 26 of the positioned heel in accordance with the desired amount of overlap of the forwardly projecting portions 20 of the side cover.

After the left forwardly projecting portion 20 of the side cover has been laid upon the heel breast, the unit which comprises the bracket 30 and the anvils 37, 38, is swung about the rod 34 to the opposite side of the carrier 44 in order to lay the right forwardly projecting portion 20 (Fig. 3) of the side cover upon the heel breast. During such operation the anvil 38 forces the margin of the right forwardly projecting portion 20 against the cutting edge 41 and after trimming the forwardly projecting portion, the margin thereof is laid in overlapping relation with the first laid margin as the roll 28 moves in a clockwise direction. The anvil 38 swings the carrier 44 in a clockwise direction against the yielding movement of the spring 52 to permit the roll 28 to move across the median portion of the breast of the heel. The axis of the rod 34 passes substantially through the center of transverse curvature of the heel breast 26.

As above stated, it is desirable that the heel shall be accurately positioned in the machine. Accordingly each of the heels is provided with jig holes or recesses 72 and 74 formed in the attaching face and the tread end of the heel, respectively, the jig holes 72 and 14 of heels of various sizes being located at uniform distances respectively from the breast 26 of the heel. The jig holes 72 are shaped to receive corresponding rounded studs 16 of a gage 18 and the jig hole 14 is shaped to receive the rounded end portion 80 of an adjustable screw 82 which is turned to permit the operator to place the heel in the machine and to remove the same therefrom. The positioned heel is securely clamped in the machine through the provision of a clamp screw 84 which may be forced against the attaching face of the heel. Having described the invention, what I claim as new and desire to secure by Letters Patent of the United States is:

1. In a covering machine, means for supporting a work piece, means constructed and arranged to trim projecting margins of a cover secured to the work piece, and means for laying the trimmed 25 projecting margins in overlapping relation to each other upon said work piece.

2. In a heel-covering machine, means for positioning a heel, a member constructed and arranged to lay the forwardly projecting margins of 30 a cover applied to the rear and side faces of the heel in overlapping relation upon the breast of the heel, and means for operating said member.

3. In a heel-covering machine, means comprising a pair of cutting edges mounted for pivotal 35 movement, a pivotally mounted cover layer and anvils, and mechanism for alternately swinging the layer and the anvils toward the respective cutting edges.

4. In a heel-covering machine, means for trimming the projecting margins of a cover which is secured to a heel to predetermined widths, and means for laying the trimmed margins in overlapping relation to each other upon the heel.

5. In a heel-covering machine, means for positioning a heel the forward margins of the side cover of which project beyond the breast of the heel, means for supporting the positioned heel, means for trimming the projecting margins of the cover to predetermined widths, and means for 50 laying the margins in overlapping relation to each other upon the breast of the heel.

6. In a heel-covering machine, means for positioning a heel the forward margins of an attached side cover of which project beyond the breast of the heel, means for successively trimming the 55 projecting margins of the cover to predetermined widths, and means for successively laying the trimmed margins in overlapping relation to each other upon the breast of the heel.

60 7. In a covering machine, a pair of members mounted for pivotal movement and constructed and arranged to trim the projecting margins of a cover secured to a work piece to predetermined widths, and means for laying the trimmed projecting margins alternately upon the work piece 65 in overlapping relation.

75 8. In a covering machine, a cutter, a carrier for supporting the cutter, and a member for laying a portion of a cover upon a work piece and for forcing a margin of the cover against the cutter to trim the margin of the cover to a predetermined width, said carrier being mounted for movement under pressure of the member to permit the member to lay the trimmed margin of the cover upon the work piece.

9. In a covering machine, a cutting blade provided with an elongated cutting edge, a carrier for supporting the cutting blade, a combined layer and anvil constructed and arranged to apply a portion of a cover to a work piece and to force the margin of the cover against the cutting blade, means for operating the combined layer and anvil, and means for operating the cutting blade lengthwise of its cutting edge, said carrier being yieldable under pressure of the combined layer and anvil to permit the same to apply the trimmed margin to the work piece.

10. In a covering machine, a carrier, trimming means comprising a pair of elongated cutting edges supported by the carrier and projecting therefrom, mechanism for applying portions of a cover to a heel and for successively forcing margins of the cover against the respective cutting edges, mechanism for moving the cutting edges lengthwise to trim said margins, means for urging the carrier to a neutral position, and means for causing said cover-applying mechanism to force the carrier from said neutral position in order to apply the trimmed margins of the cover in overlapping relation upon the heel.

11. In a covering machine, means for positioning and clamping a heel provided with an attached side cover the forward margins of which project from the breast of the heel, a pivotally mounted carrier which is normally positioned adjacent to the median portion of the breast of the heel, trimming means supported by the carrier and comprising a cutting edge which faces widthwise of the heel, resilient means for normally retaining the carrier in said position, a pivotally mounted cover layer, a pivotally mounted anvil, means for swinging the cover layer and the anvil progressively to apply portions of one of the projecting margins of the cover to the breast of the heel and to force other portions of said margin against the cutting edge, and means for moving the cutting edge lengthwise to trim the projecting margin supported by the anvil to a predetermined width, said carrier being movable under pressure to permit the cover layer to apply the remaining unlaid portions of the trimmed cover margin to the breast of the heel.

12. In a covering machine, means for positioning and clamping a heel provided with an attached side cover the forward margins of which project from the breast of the heel, a pivotally mounted carrier, resilient means constructed and arranged normally to retain the carrier adjacent to the median portion of the breast of the heel and to permit the carrier to be swung under pressure transversely of said breast from said normal position, trimming means supported by the carrier and comprising a pair of cutting edges which face toward opposite sides respectively of the heel, a pivotally mounted cover layer, pivotally mounted anvils, and means for swinging the cover layer and the anvils progressively to apply the projecting margins of the cover to the breast of the heel and to force the anvils against the respective cutting edges, means for moving the cutting edges lengthwise, and mechanism for moving said carrier against yielding pressure of said resilient means as the layer and the anvils are moved in order to apply the trimmed cover margins in overlapping relation to the breast of the heel.

13. In a cover-trimming machine, means for clamping a heel, a carrier mounted for movement in an arcuate path, a cutting blade sup-

- ported by the carrier and provided with a pair of elongated cutting edges projecting from the carrier, mechanism for operating the blade, resilient means for normally retaining the carrier in a neutral position, a member mounted for movement in an arcuate path, and means constructed and arranged successively to force the member against the cutting edges and to move the carrier against the pressure of said resilient means, said member comprising means for applying a cover to the heel and anvils which are constructed and arranged to cooperate with the respective cutting edges to trim margins of the cover before such margins are applied to the heel.
14. In a covering machine, a carrier, a flexible blade supported by the carrier and mounted for oscillation relatively to the carrier, said blade being provided with elongated cutting edges which project beyond the carrier, means including a member constructed and arranged to apply portions of a cover to a work piece and to force upstanding margins of the cover against the respective cutting edges, and mechanism for operating said means.
15. In a covering machine, means for positioning and clamping a heel, a pivotally mounted carrier, resilient means for normally maintaining the carrier in a predetermined position and for permitting the same yieldingly to swing transversely of the heel, a cutting blade supported by the carrier and provided with a pair of elongated cutting edges projecting beyond opposite sides of the carrier, said blade being mounted for movement lengthwise of its cutting edges, means for operating the blade, and a heel-cover layer and anvils movable over the breast of the heel toward and away from opposite sides of the carrier in paths arranged in substantially concentric relation with the transverse curvature of the breast of the heel.
16. In a covering machine, means comprising a pair of elongated cutting edges, means for moving the cutting edges lengthwise, a movable member comprising a roll and a pair of anvils positioned at opposite sides of the roll, and means for alternately moving the member relatively to the respective cutting edges to force margins of a cover applied to a work piece against said edges respectively thereby to trim said margins and to lay the trimmed margins in overlapping relation upon the work piece.
17. In a heel-covering machine, means for supporting a heel having an attached side cover the forward portions of which project beyond the breast of the heel, a carrier, a cutting blade supported by the carrier and provided with elongated cutting edges projecting from opposite sides respectively of the carrier and spaced a substantial distance from the breast of the heel, mechanism for operating the cutting blade, and a member for laying the portions of the cover projecting beyond the breast of the heel against the lateral margins of said breast and for forcing the margins of said forward portions of the cover against the cutting edges respectively to trim the margins of the cover, said carrier being movable in opposite directions under pressure of said member to permit the member to lay the trimmed margins of the cover in overlapping relation upon the central part of the breast of the heel.
18. In a covering machine, a pair of cutting edges, means for operating the cutting edges, a pair of anvils for cooperating with the respective cutting edges to trim margins of a cover portions of which have been attached to a work piece, a tool for applying the margins of the cover to the work piece, and means for operating the tool and the anvils, said cutting edges being displaceable under operating pressure of the respective anvils to permit the tool to lay the trimmed margins in overlapping relation upon the work piece.
19. In a covering machine, means for positioning and clamping a heel, a pivotally mounted carrier, a blade provided with a pair of elongated cutting edges, mechanism for moving the blade lengthwise of its cutting edges, and a unit movable toward opposite sides of the carrier and arranged to swing the carrier, said unit comprising members constructed and arranged to inturn a cover toward the heel, anvils for forcing the respective inturned margins against the cutting edges, and a resilient roll positioned between the anvils.

LEWIS J. BAZZONI.
